PADLOCK

Elmer B. Stone, New Britain, Conn., assignor
to The American Hardware Corporation, New
Britain, Conn., a Corporation of Connecticut

Application December 5, 1930. Serial No. 500,222

3 Claims. (Cl. 70—103)

My invention relates to that class of locks embodying a case having a locking shackle projecting from one end thereof, and an object of my invention, among others, is the construction of a lock of this type with means for preventing its operation without the use of a key.

One form of a lock embodying my invention and in the construction and use of which the objects herein set out, as well as others, may be attained is illustrated in the accompanying drawing, in which—

Figure 1 is a side view of a padlock embodying my invention.

Figure 2 is a view in lengthwise section through the same on a plane passing through the axis of the arms of the shackle.

Figure 3 is an end view of the lock.

Figure 4 is a view in cross section on a plane denoted by the dotted line 4—4 of Figure 2.

Figure 5 is an isometric view of one end of the key plug.

It has been found possible with different types of padlocks embodying a shackle movably mounted in the lock to engage one arm of said shackle with a locking bolt within the case, to surreptitiously open said lock by means of a series of blows delivered in a certain manner, the parts being held in the position caused by said blows by placing a strain upon the shackle or other parts. By skillfully employing this means it has been found possible to unlock the padlocks without the use of a key. My invention illustrated and described herein seeks to avoid such unauthorized opening of a padlock.

My improved structure embodies a case 5 having a hole 6 to receive the long arm 7 of a shackle mounted upon a spring 8 in the bottom of said hole, the short arm 9 of the shackle engaging within a recess 10 projecting inwardly from the end of the case. A key plug 11 is rotatably mounted within the case, this plug having the usual key slot, and the case having tumblers 12

of the pin type cooperating with a set of pin tumblers in the key plug to permit rotation of the plug when the tumblers are properly positioned by a key inserted in the key slot. All of the parts thus far described are of old and well known construction and will be readily understood by those skilled in the art, my invention residing in features now to be described.

The short arm 9 of the shackle is provided, near its end, with a notch that is entered by the end of a locking bolt 13 slidably mounted in a hole opening into the recess 10, this bolt

being seated against a spring 14 in the bottom of said hole which spring forces the bolt normally into the notch in the shackle arm. The bolt is provided on one side with a notch 15 within which an actuating finger 16 projecting from the end of the key plug 11 extends, the notch 15 being enough larger than the finger to permit endwise movement of the bolt 13 sufficiently to disengage its nose 17 from the notch in the short arm of the shackle, this construction also being present in prior devices.

In carrying my invention into effect I provide a stop in the form of a lip 18 extending into the notch in the short arm of the shackle from one side of said notch, and I also provide a retaining lip 19 extending from the nose 17 of the shackle into position to engage the stop lip 18. It will thus be seen that the engagement of the stop and retaining lips 18 and 19 will make it practically impossible to effect backward movement of the locking bolt 13 by concussion.

It is desirable, for many reasons, that the locking bolt 13 shall be non-rotatable, having a lengthwise movement only. Simplicity of construction may be mentioned as one of these reasons. I have therefore utilized the endwise yielding movement of the shackle to effect my purpose in this respect. In order to enable the bolt 13 to be readily moved backward by the operation of the finger 16 in a rotation of the key plug 11 I bevel the engaging edges of the lips 18 and 19 to a slight extent. This will cause an inward movement of the shackle against the tension of the spring 8 as the bolt 13 is forced backwardly by the finger 16 in the unlocking operation. To permit such inward movement of the shackle the bottom of the recess 10 is spaced from the end of the short arm 9 of the shackle.

Such parts of the lock as have not been herein specifically set forth will be understood to be of old and well known construction and not requiring further explanation.

I claim—

1. A padlock including a case, a shackle mounted for yielding movement within the case and having a recess with an upturned lip at the mouth of said recess, a locking bolt mounted for sole longitudinal reciprocating movement within the case and having a downturned lip forming a recess between said lip and the body of the bolt for reception of the lip on the shackle, the end of the bolt being receivable in the recess in the shackle, and means for operating said bolt.

2. A padlock including a case, a shackle

mounted for yielding movement within the case and having a recess with an upturned lip beveled on its inner edge at the mouth of said recess, a locking bolt mounted for sole longitudinal reciprocating movement within the case and having a beveled downturned lip forming a recess between said lip and the body of the bolt for reception of the lip on the shackle, the end of said bolt being receivable in the recess 10 in the shackle, and means for operating said bolt.

3. A padlock including a case, a shackle

mounted for yielding movement within the case and having a recess with an upturned lip at the mouth of said recess, a locking bolt mounted for sole longitudinal reciprocating movement within the case and having a downturned lip 80 forming a recess between said lip and the body of the bolt for the reception of the lip on the shackle, the end of the bolt being receivable in the recess in the shackle, and a key plug having an actuating finger engaged with said bolt for operation thereof. 85
